[57] CLAIM

The ornamental design for a toy truck/trailer combination, as shown and described.

DESCRIPTION

FIG. 1 is a top view of a toy truck/trailer combination

showing my new design;

FIG. 2 is a side view of the toy truck/trailer combination of FIG. 1, on a reduced scale, showing my new design;

FIG. 3 is a bottom view of the toy truck/trailer combination of FIG. 2 showing my new design;

FIG. 4 is a rear view of the toy truck/trailer combination of FIG. 2 showing my new design;

FIG. 5 is an opposed side view of the toy truck/trailer combination showing my new design;

FIG. 6 is a side view of the truck only of the toy truck/trailer combination showing my new design;

FIG. 7 is a front view of the truck of FIG. 6 showing my new design;

FIG. 8 is a top view of the truck of FIG. 6 showing my new design;

FIG. 9 is a rear view of the truck of FIG. 6 showing my new design;

FIG. 10 is a top view of the trailer only of the toy truck/trailer combination showing my new design;

FIG. 11 is a rear view of the trailer of FIG. 10 showing my new design; and,

FIG. 12 is a right side view of the trailer of FIG. 10 only showing my new design.
